AUTHUR F. ROWELL, OF SPRINGFIELD, MASSACHUSETTS.

CARBURETER.

1,151,286.

Specification of Letters Patent. Patented Aug. 24, 1915.

Application filed September 29, 1914. Serial No. 864,065.

To all whom it may concern:

Be it known that I, ARTHUR F. ROWELL, a subject of the King of Great Britain, residing at Springfield, in the county of Hampden and State of Massachusetts, have invented certain new and useful Improvements in Carbureters; and I do hereby declare the following to be a full, clear, and exact description of the invention, such as will enable others skilled in the art to which it appertains to make and use the same.

This invention relates to carbureters and the primary object of the invention is the provision of a carbureter which is constructed for utilizing a minimum amount of petrol or gasolene, and one which will properly vaporize the volatile fuel used at all speeds.

Another object of this invention is the provision of a carbureter which embodies a throttle and a jet disposed in alinement with each other, about which throttle and jet are positioned slidably movable choke sleeves for varying the area about the jet and the throttle for increasing or decreasing the passage of air and gas into and through the carbureter.

Another object of this invention is the provision of a carbureter which has a plurality of air openings formed in the casing thereof, which forms an air brake when running down a long incline with the throttle closed and also takes in a quantity of pure air, cleaning and cooling the engine cylinder, relieving or breaking the vacuum therein and by so doing stops or prevents oil from being sucked above the piston while traveling down a long incline, which prevents excess carbonization.

With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters designate like or corresponding parts throughout the several views, and in which:—

Figure 1 is a central sectional view through the improved carbureter, and Fig. 2 is a fragmentary view in side elevation of the carbureter.

Referring more particularly to the drawings, 1 designates the outer casing of the carbureter which has transversely extend-

ing projections 2 and 3 formed thereupon. The transversely extending projection 3 is provided with an opening 4 formed therein which receives the float 5 of the carbureter. The float 5 is mounted about a valve stem 6, which valve stem has a substantially frusto-conical shaped valve 7 mounted upon the lower end thereof, which controls the inlet of gasolene into the chamber 4, through the opening 8 and the bores 9, which openings are formed in the extension 10 formed upon the projection 3 and in the pipe 11 which is connected to the projection 3 by means of a collar 12.

The casing 1 of the carbureter has an opening or passage way 14 formed therein and extending transversely through the same adjacent the bottom thereof, which opening has a set screw 15 inserted therein for forming a closure for the same. An inclined passage way 16 communicates with the passage way 14 and with the interior of the projection 3, for permitting gasolene or other suitable volatile liquids to pass from the chamber 4 into and through the passages 16 and 14 for forcing upwardly through the jet tube 17. The jet tube 17 is mounted interiorly of the casing 1 and has its ends screw threadably mounted in an opening 18, which has communication with the passage way 14. The jet tube 17 is provided with a vertical bore 19 which terminates inwardly of the upper end of the tube and has communication with the plurality of transversely extending openings or passage ways 20, which extend outwardly through the sides of the head 21 of the jet tube 17. The vertical bore 19 has a needle valve 22 positioned therein, which is controlled by the adjustability of a rod 23 for controlling the amount or quantity of volatile fuel which passes through the bore 19.

The casing 1 has an elbow joint 25 secured to the upper end thereof, which forms a gas outlet for the carbureter and has communication with the combustion chambers of an internal combustion engine (not shown). The elbow 25 is secured to the upper end of the casing 1 in any suitable manner, such as by transversely extending ears 26 and bolts 27 which pass through the ears and are held therein for holding the ears in binding engagement with each other by nuts 28.

The elbow 25 has an enlarged throttle stem supporting guideway 29 formed integrally therewith, in which guideway is

adjustably seated the throttle stem 30. The throttle stem 30 is provided with external screw threads which coact with internal screw threads formed upon the guideway 29, whereby the insertion of the throttle cone 31 which is secured to the inner depending end of the throttle stem 30 may be regulated.

The casing 1 has mounted therein a throttle choke sleeve 32, which has an interiorly extending enlargement 33 formed upon its upper end as is clearly shown in Fig. 1 of the drawings. The throttle choke sleeve 32 has detachably secured to its lower end a jet choke sleeve 33, which is positioned about the jet tube 17 for regulating the passage of air through the opening formed in the transverse projection 2 into the carbureting chamber of the carbureter, which carbureting chamber is formed within the sleeves 32 and 33. The sleeve 33 projects downwardly across the communicating openings between the interior of the casing 1 and the transverse projection 2, regulating the magnitude of this opening and consequently the inflow or ingress of air into the lower most portion of the sleeve 33 for passage upwardly about the jet tube 17. The sleeve 33 has its bores constricted adjacent the upper end thereof, as is clearly shown in drawings, and the walls of the sleeves taper outwardly or diverge as they extend downwardly from the constricted portion so that the opening or area between the outer surface of the head of the jet and the inner surface or wall of the sleeve will be increased upon the upward movement of the sleeve within the casing 1.

The sleeve 32 has a bolt 34 secured thereto, which extends out of the casing 1 through a slot 35 and has connected thereto an angled lever 36, which is pivotally mounted upon an extension 37. The angled lever 36 has a plurality of longitudinally spaced openings 38 formed therein which are connected to any suitable type of controlling rod or lever (not shown), by means of which the elevation of the sleeves 32 and 33 within the casing 31 may be varied to suit various conditions and for the regulation of the speed of generation of gases within the carbureter.

The casing 1 is provided with a plurality of circumferentially spaced openings 39 formed therein, which openings are positioned above the upper end of the sleeve 32, when the sleeve is in its downward position. The openings 39 are provided for the inlet of air, for forming a fairly good brake when running down long inclines with the throttle closed and also to permit of the scavenging of the combustion chambers of the engine (not shown) to which the carbureter is connected, for the prevention of the carbonization of oil within the cylinders above the piston and also for relieving the vacuum therein.

In the operation of the improved carbureter heretofore described the volatile liquid enters the vertical bore 19 of the jet tube 17 through the opening or passage ways 16 and 14 and 18, and the amount flowing therethrough is regulated by the adjustment of the needle valve 19. The volatile liquid passing upwardly through the bore 19 is deflected from the jet tube into the interior of the sleeve 33 through the transversely extending passage ways 20. Upon the egressing of the volatile fuel or liquid from the passage ways 20, it is vaporized through confusing contacts with air which passes inwardly into the sleeve 33 through the opening 40, which is left beneath the lower end of the sleeve 33 and the inner wall of the extension 2. The air entering the sleeve 33 through the opening 40 passes upwardly about the jet tube 17 and comes in contact with the volatile fuel passing out of the passage ways 20. The air contacting with the volatile fuel vaporizes the same and the combined air and fuel which form an impregnated combustible gas passes upwardly through the sleeve 32 and therefrom by passing about the throttle cone 31 and upwardly through the elbow 25 to the combustion chambers of an engine.

The throttle lever 36, which is connected to the sleeve 32 is operated or moved enough for moving the sleeve 32 upwardly for closing the openings 39, and moving the inwardly extending enlarged portion 33 of the sleeve out of engagement with the surface of the cone 31 for permitting of the passage of the impregnated air upwardly through the same. By moving the sleeve 32 upwardly the jet choke sleeve is also moved upwardly for increasing the area about the jet. The throttle cone 31 is adjusted so that the area or space about the circumference of the same, interiorly of the sleeve 32 is greater than the space about the head 21 of the jet tube 17. The further actuation of the lever 36 will increase the space or area about the throttle cone 31 and about the head of the jet tube 17, as is clearly shown by reference to the drawing. By the construction of the sleeves 32 and 33 so that the space about the throttle cone 31 is of greater area than the space about the head 21 of the jet tube 17, the air velocity is greatest at the jet which permits of a more proficient vaporization of the volatile liquid.

From the foregoing description taken in connection with the accompanying drawings the advantages of the construction and of the method of operation of the improved carbureter will be readily apparent to those skilled in the art to which this invention appertains and, while in the foregoing description, the principle of the operation of this invention has been described together with various features of construction, it is to be

understood that certain minor features of construction, combination and arrangement of parts may be altered to suit practical conditions provided such alterations are comprehend within the scope of what is claimed.

What is claimed is:

1. In a carbureter, an outer casing, a throttle cone adjustably positioned within said casing, a jet tube extending within said casing, and a pair of sleeves positioned within said casing and about said throttle cone and jet tube for regulating the flow of air into and the flow of gas out of said casing.

2. In a carbureter, an outer casing having a throttle cone adjustably positioned therein, a jet tube extending upwardly within said casing, a throttle choke sleeve positioned within said casing about said throttle cone, a jet choke sleeve positioned within said casing about said jet tube, and means for moving said jet choke sleeve and said throttle choke sleeve vertically within said casing synchronously with each other for regulating the inflow of air into and the outflow of gases out of said casing.

3. In a carbureter, a casing, a throttle cone adjustably suspended within said casing, a jet tube extending upwardly within said casing, a volatile fuel containing chamber communicant with said jet tube, a needle valve for controlling the passage of volatile fuel through said jet tube, a throttle choke sleeve adjustably mounted within said casing, a jet choke sleeve adjustably mounted in said casing and connected to said throttle choke sleeve for movement synchronously therewith, said throttle choke sleeve and said jet sleeve having constricted portions, the side walls of said jet choke sleeve and said throttle choke sleeve diverging from said constricted portions whereby the area about said jet and said throttle cone will be increased upon the upward movement of said sleeve within said casing, said jet choke sleeve controlling the inlet of air thereinto.

In testimony whereof I affix my signature in presence of two witnesses.

ARTHUR F. ROWELL.
